LIFE PRESERVER

Jacob J. Podell, New York, N. Y.

Application March 1, 1950, Serial No. 147,095

7 Claims. (Cl. 9—17)

1

The present invention relates to life preservers and more particularly to a life preserver which may be inconspicuously worn in collapsed condition, but which may be readily positioned and inflated for supporting a person in water.

The present invention is an improvement upon and extends the field of usefulness of life preservers of the type shown in my prior United States Patent No. 2,463,641 granted March 8, 1949.

In some instances it is desirable that when inflated and ready for use a life preserver be positioned adjacent a person's shoulders so that it may tend to hold the head out of the water; this is of great value in connection with a temporarily unconscious person as it gives the wearer a chance to regain his senses and take steps to save himself. While this high up position on a person's body is desirable it has heretofore been difficult to achieve with a life preserver that could normally be inconspicuously worn with ordinary clothing.

An object of the present invention is to provide a new and improved life preserver.

Another object of the invention is to provide a new and improved life preserver which may be inconspicuously worn and yet which may be readily positioned adjacent the shoulders and neck of a user and inflated for use.

Another object of the invention is to provide a life preserver of the above character which meets the requirements of the Navy and other Government departments or bureaus.

Still another object of the invention is to provide a life preserver having improved means for retaining it on the body of a user.

A still further object of the invention is to provide an improved life preserver adapted to support a wearer's face upwardly away from the water.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a perspective view showing one form of the present invention in non-inflated condition;

2

Fig. 2 is a perspective view showing the life preserver of Fig. 1 assembled with ordinary trousers;

Figs. 2a and 2b are fragmentary views showing alternative means for connecting the present life preserver with trousers;

Fig. 3 is a sectional view taken along the line 3—3 of Fig. 2;

Fig. 4 is a sectional view taken along the line 4—4 of Fig. 2;

10 Fig. 5 is an enlarged fragmentary view of means which may be used to retain the life preserver adjacent the shoulders of a user; and

Fig. 6 is a perspective view showing the life preserver of Figs. 1—5 in inflated condition and disposed adjacent the shoulders and neck of a wearer.

Referring generally to the drawings, there is shown in Fig. 1 one embodiment of the invention in collapsed or non-inflated condition. The device comprises an inflatable belt-like portion 1, connected with and extending along a fabric strip 6 for encircling the waist of a user, from which depend spaced inflatable pockets or chambers 2 and 3, each of the pockets being provided with strap means 4 and 5 for holding the device to the shoulders or upper arms of a person. The entire device illustrated in Fig. 1 may be normally worn in inconspicuous manner at the interior of an ordinary pair of trousers (Fig. 2) and is adapted to be worn in inflated condition as illustrated in Fig. 6. From the latter view it will be clear that the present life preserver is so worn adjacent the shoulders and neck of a person that it is adapted to support a person's head out of the water and with the face disposed upwardly away from the water. The device will now be described in greater detail, first the inflatable portion and thereafter the straps for securing it adjacent the shoulders of a user.

40 The inflatable belt-like portion 1 of the life preserver includes substantially gasproof or water impermeable material forming a passageway for conducting inflating gas to the pockets 2 and 3 that normally hang downwardly from the belt portion 1 and are in communication with the interior 9 of the passageway. Air or gas supplied to the belt passageway may find its way through a connecting port to the interior of the pockets or chambers. The inflatable belt portion 1 is shown carried by a fabric strip 6 for encircling a person's waist; the inflatable portion may be connected with the strip 6 in any manner, for example, by adhesive, stitching, spaced extensions 7, or otherwise.

45 50 55 The construction of each inflatable pocket is

the same and hence a description of one will suffice for both. Each pocket comprises an outer wall 10 and an inner wall 11 joined together along adjacent edges 31 to form a closed chamber 14 between the two wall portions. The chamber 14 is in communication with the passageway interior 9 through a connecting conduit 15. When deflated or collapsed as in Fig. 1, the inner and outer wall portions 10 and 11 of the pockets lie closely adjacent each other and the "infolded" relationship provides a readily inflatable chamber of relatively small size. When gas is supplied to the passageway interior 9 it finds its way down through the connecting openings 15 to the space 14 between the inner and outer pocket walls and the inner wall 11 may force outwardly through the pocket opening 12, to the relationship illustrated in Fig. 6. Inflation may be assisted by first pulling the inner lining 11 out through the pocket opening 12 and thereafter inflating. Preferably portions 8 of the fabric strip 6 extend downwardly along and are connected with edge portions of the openings 12 for assisting in supporting the pockets.

Gas may be supplied to the interior passageway 9 from any suitable puncturable cartridge (not shown) located within cylinder container 18. The latter container 18 may be provided with any well known device for puncturing the interiorly located cartridge to release the contained gas, and such device may be operated through exteriorly disposed lever 16 and cord and pull button 17.

In addition to the containers 18 and 18a with their gas cylinders there is also preferably provided an auxiliary inflating means comprising an oral inflating tube 26 and 26a connected with each of the pockets through suitable inflating valves 27 and 27a. In the event of failure of the mechanism of the containers 18 or 18a to inflate the pockets, or in the event of loss of gas over a considerable period of time, the oral inflating tubes may be utilized for supplying air to or replenishing the air which has leaked out of the pockets.

Preferably the interior passageway 9 is divided as at 13 intermediate the two pockets 2 and 3 to form two entirely separate compartments, one of which may be inflated by the inflating means 18 and the other of which may be inflated by inflating means 18a. In this manner puncturing of the passageway or pockets at one side of the division does not result in complete loss of air.

The pockets 2 and 3 may be made of any suitable size. Preferably some optimum size will be chosen which is adapted to use with belts 1 of any length.

The belt portion 1 may be worn around a person's waist within the interior of any ordinary pair of trousers so that the trousers conceal the life preserver from view. The belt 1 and pockets 2 and 3 are substantially flat in non-inflated condition and lie closely adjacent the body of the wearer so that it is not easy to ascertain from merely looking at a person whether or not the life preserver is being worn. While any suitable means may be provided for attaching the ends of the supporting strip 6 about the waist of a wearer this is preferably achieved by some quick-release means such as snap fasteners mounted adjacent the ends of the strip. With such fasteners projections 24 on one portion of the fastener snap tightly into apertures 25 on the other portion of the fastener; the apertured portion of such a fastener may be mounted adjacent one end of

the strip 6 and the projecting portion of the other part of the fastener adjacent the opposite end thereof so that upon bringing the ends together they may be snapped firmly into engagement. Several sets of such fasteners may be provided adjacent the ends of the strip, or at other locations therealong, to comfortably accommodate waists of different circumference and also to facilitate suitable adjustment of the device about the neck of a wearer when worn in the relationship of Fig. 6.

While the life preserver may be worn at the interior of the trousers without a positive attachment thereto, it is preferred that the life preserver be actually attached to the trousers so that it always accompanies them. This may be achieved by suspensory loops 32 connected with the belt-like strip 6 at spaced intervals, the suspensory loops 32 facilitating attachment to the suspender buttons 33 with which trousers are generally provided. These loops 32 hold the life preserver to the inner sides of the trousers at their upper portion and in effect serve as an additional lining for the trousers. The life preserver is in this manner detachably connected with the usual pair of trousers without providing any special attachment means. In instances where the trousers are provided with suspender buttons on their exterior surfaces instead of the interior as in Fig. 2, the suspensory loops 32 may merely be turned over the uppermost edge 34 of the trousers and connected with the exterior suspender buttons in a manner similar to that shown in Fig. 2.

While the suspensory loop attachment of the present life preserver is preferred it will be understood that any other suitable means for connecting the life preserver with trousers may be provided. For example (Fig. 2a) the encircling strip 6a could be provided with a slide fastener element 37 adapted to cooperate with a complementary slide fastener element 38 carried by the upper portion of the trousers. Another alternative construction for detachably securing the life preserver with trousers is shown in Fig. 2b where the upper portion of the trousers is provided with apertured snap fastener elements 40 adapted to receive complementary projecting snap fastener portions 41 carried by a life preserver belt-like strip 6b. Regardless of whether the life preserver is attached through the medium of suspensory loops, slide fasteners, snap fasteners, or any other similar means, it may be readily attached to and detached from the trousers.

In the event a slide fastener is utilized for securing the life preserver to the trousers it is preferred that the portion of the fastener carried by the life preserver be located away from the edge of the belt, so that when worn as shown in Fig. 6 any metal edge is disposed away from the neck of a wearer minimizing the chances of injuring him. Also, in the event snap fastener means is utilized for attaching a life preserver to a pair of trousers it is preferred that the projecting fastener portions 41 be carried by the life preserver as, if they are carried by the trousers, they might dig into the sides and back of a person during times when the life preserver is removed from the trousers.

When worn beneath a pair of trousers the inflatable pockets 2 and 3 may have the side pockets 19 of the trousers extending into them through the openings 12 and 12a and the wearer may use his trouser pockets in normal manner without any interference with the life preserver pockets. The cloth pockets 19 of the trousers serve as pro-

TECTIVE layers and minimize the danger of any object in the pocket coming into contact with the life preserver pocket 11 and puncturing it. This is not essential however, as the trouser pockets need not extend into the life preserver pockets. Pockets 19 of the trousers may extend loosely into the preserver pockets or it may, in some instances, be desired to positively attach the trouser pockets to the life preserver pockets. This may be achieved by a fastener such as used with garters to hold up men's hose; a U-shaped member 21 fits around a projection 22 carried by a flexible tab 23, an adjacent cloth layer of the trouser pocket 19 being clamped or gripped by such attachment and held in the pocket adjacent the inner life preserver pocket layer 11. If this latter construction is used, the opposite end of the flexible tab 23 is preferably secured by some readily releasable snap fastener 28, with the preserver pocket inner layer 11; as the trouser pocket and inner layer 11 are pulled apart the snap fastener automatically releases and allows separation. Any other means may be provided, in lieu of a garter type fastener, for interconnecting a trouser pocket 19 and the inner lining 11; for example, the snap fastener 28 could connect them directly or a slide fastener as shown in Fig. 2a could be employed.

To retain the life preserver in position adjacent the shoulders and neck of a wearer there are provided suitable adjustable retaining straps, shown in Fig. 1 adjacent rearward edges of the pockets 2 and 3 and the openings 12 thereto. The life preserver is shown inflated ready for use in Fig. 6, with the retaining straps encircling the shoulders or upper arms of the wearer, and strap means extending across his chest. In this relationship the belt portion 1 and strip 6 extend loosely around the neck of the wearer. The retaining straps of each pocket of the life preserver are similar and a detailed description of those of one pocket will serve for both.

As shown in Fig. 1 the strap means for retaining the life preserver at the shoulders comprises a single endless strap; the strap portion adjacent each pocket 2 and 3 is so constructed and arranged that a person may thrust his hand and arm through appropriate openings or loops and position the life preserver adjacent his shoulders and neck. To achieve this the upper connecting portion 45 (which is connected with the belt-like strip 6) extends downwardly to form strap portion 46 positioned adjacent the opening 12 of the pocket; the lower end of this downwardly extending portion 46 then passes through an attachment ring 47 and upwardly to form strap portion 48, which in turn passes through a second attachment ring 50 adjacent the upper portion of the pocket and has its free end 52 provided with a snap fastener element or any other enlargement 53 that serves to prevent unintentional withdrawal of the free end through the strap guiding and retaining element 54. Thus the strap is continuous from the upper belt portion 45 to its free end 52. The upper ring 50 may be attached to the life preserver by a loop 56 and the downwardly extending strap portion 46 may be retained in position adjacent the pocket 2 by spaced retaining loops 57 and 58. The upwardly extending strap portion 48 may be readily spaced from the attached strap portion 46 so that these two strap portions may cooperate to form a loop of sufficient dimension to readily receive the arm and shoulder of a wearer. The other depending pocket 3 is provided with similar strap means

formed by a continuation of the common belt-like portion 45.

The connecting strap part 45 may be stitched directly to the belt-like strip 6 but it is preferred to have it pass loosely through slots 30 adjacent the pockets, so that it may pass along the outer face of the strip 6. This allows the strap part 45 to shift longitudinally when arranging the life preserver at the shoulders and also makes it available for connection by a grappling hook or boat hook.

While any suitable material may be utilized for the strap it is preferred that it be some relatively strong and light material which tends to retain its shape against objectionable twisting. The nylon fabric strap material used with parachutes, and about $\frac{1}{2}$ " in width, serves well and is not subject to rapid deterioration due to exposure to salt water, rotting or otherwise. While the term "strap" is used for the means for attaching the life preserver to the body of the wearer it will be understood that the material may be of any suitable shape, for example, flat, circular or otherwise; the term "strap" is intended to include such and is used for convenience of description.

When the life preserver is positioned at the shoulders of a wearer, as in Fig. 6 and as will be further described hereinafter, it is desirable that the inflated pockets be held in position adjacent the chest of the wearer. This is provided by the cooperating straps shown adjacent the lower portion of each of the pockets 2 and 3. A strap 60 (Figs. 1 and 6) is secured at one end with the attachment ring 47, and extends through retaining loops 61 and 62 attached to the pocket 2 and then doubles back toward the retaining ring 47 so that a snaphook 64 carried adjacent the free end of the strap 60 may be engaged with the attachment ring 47. When in use adjacent the shoulders, the snaphook 64 of the pocket 2 and the similar snaphook 64a of the pocket 3 are disengaged from their attachment rings 47 and 47a and hooked together across the chest, as shown in Fig. 6.

In the collapsed relationship of Figs. 1 and 2 the chest straps 60 and 60a hold the arm loop straps close to the pocket walls. However, by disengaging the snaphooks 64 and 64a from their attachment rings 47 and 47a the "free" or spaceable strap portion 48 of the arm loop may be readily separated from the attached portions of the arm loop strap to facilitate entry of an arm into the loop. Any confusion is thus minimized in connection with positioning the life preserver adjacent the shoulders as there is only one strap portion (48 and 48a) of each pocket which may be spaced from the other strap portion to provide the arm loops.

While the straps may be attached to any suitable portions of the pockets 2 and 3 it is preferred that they be adjacent the openings 12 and 12a as in this relationship the straps and their rings and snaphooks are normally so located within the trousers that they cannot readily injure the wearer. Also, the oral inflating tubes 26 and valves 27 are exposed at the rear or extreme side portions of the pockets where they are not likely to injure the wearer when the life preserver is worn in collapsed condition.

A minimum of motions is required to shift the life preserver from a normal or collapsed position about the waist of the wearer to a position adjacent the shoulders, where it may be

inflated to support one in water. While various steps may be employed in various sequences, to thus shift the life preserver it will be found very satisfactory to first remove the suspensory loops 32 from the suspender buttons of the trousers. If the trouser pockets have been worn within preserver pockets 2 and 3 they may now be pulled out. The latter may be done by pulling the trouser pockets out of the preserver pockets. If the trouser pockets have been secured to lining 11 of the pocket by garter-like or snap attachment, a pull serves to disengage them. The belt portion 1 may now be pulled upwardly and draped around the neck, the free ends of the strip 6 being snapped together by appropriate fasteners 24-25 so as to give a comfortable encirclement around the neck. An alternative method is to remove the suspensory loops 32 from the buttons, snap the fasteners 24-25 together for convenient size, and then place the preserver 20 over the head and around the neck.

After arranging the life preserver around the neck by procedures such as the above the arms may be thrust through the loops provided by the downwardly extending strap portions 48 and 46 and these straps pulled toward the shoulders, to encircle the upper arms or shoulders. The spaceable portions 48 and 48a of the straps are so positioned that a user can readily see them and insert his arms through the obvious and logical opening. The snaphooks 64 may then be released from attachment rings 47 and 47a and connected across the chest. Gas release buttons of containers 18 and 18a may then be operated to release gas, which passes into the passageway of belt 1 and thence into the chambers formed by the inner and outer pocket walls. The inner pocket walls may at this time be out of the outer walls, having been pulled out upon removal of the trouser pocket from the life preserver pocket, or in the event the life preserver has been worn around the waist without connection between the trouser and life preserver pockets, entry of gas into the space 15 between the walls urges the inner layer 11 out through the pocket opening.

As shown in Fig. 6 the inflated belt extends loosely around the neck of the wearer and the inflated chambers are retained high up on the shoulders of the wearer and adjacent his chest. The connecting straps and snaphooks hold the inflated chambers adjacent the chest. Even though a person may fall into the water face down, the inflated chambers will turn him over so as to face upwardly. The normal tendency of the inflated life preserver is to hold a person's head upwardly with his face out of the water. The rear portion of the inflatable belt 1 extends around the back of the neck and provides a comfortable rest.

The oral inflating tubes 26 (Fig. 6) preferably of rubber or other flexible material, are disposed so that their ends are readily available to the mouth of one wearing the life preserver. These tubes may be of any suitable length. The oral inflating means may be connected with the pockets of the life preserver at any suitable locations; they are shown adjacent lower parts in Fig. 1 as this is a convenient location which does not interfere with wearing the life preserver in collapsed or inflated conditions. Likewise, the containers 18 and 18a may be located on the belt at any locations where they do not interfere with wearing the device collapsed or inflated.

The present life preserver is unique in that it occupies a minimum of space and may be concealed on the wearer so as to provide complete freedom for work or play. The inflatable belt connects with the double folds of the life preserver pockets which constitute the buoyant air chambers. These pockets may receive the pockets of a conventional pair of trousers. An arrangement of light nylon straps is adapted to form a stout harness for the life preserver and the straps are sufficiently strong to receive grappling hooks or a boat hook without breaking so as to injure the wearer. The inflatable belt portion may form a collar around the neck of a user and the inflatable pocket chambers rest on his chest and adjacent his shoulders so as to make capsizing practically impossible; the head of the wearer is sustained above the water at all times so that even if he may be unconscious there is little possibility of drowning.

It will be seen that the advantages and protective features of the present life preserver are numerous. It includes the desirable features rendering it adaptable for use on ships, boats and launches and is normally adapted for use as a supplementary aid to the conventional life jackets or life preservers utilized by the Navy, Coast Guard and other activities. The present life preserver may be inconspicuously worn beneath a pair of trousers without any attachment thereto or it may be used with a conventional pair of trousers by attaching it to the suspender buttons of the trousers. If desired it may also be attached to trousers by snap fasteners, a slide fastener or any other appropriate means. Temporary attachments to the pockets of the trousers may be provided by garter-like attachments similar to those used for supporting stockings. The life preserver is relatively light and not bulky so that when worn inside the trousers it is normally concealed and cannot be readily detected by visual observation. By reason of its compactness and lightness the life preserver is well suited for use by personnel of submarines and aircraft. It may be readily removed from a position about the waist and placed in condition for usage adjacent the shoulders. Inflation may be obtained by releasing of carbon dioxide or other gas from the cylinder containers or it may be inflated by oral inflating tubes and valves. Two separate air chambers are provided so that even if any part of one chamber should accidentally be punctured the other will be available to hold gas and support a person in the water.

While the life preserver is shown in Fig. 6 with the inflated chambers of each pocket at the front of a wearer, the portions of the chambers formed by the inner walls 11 and 11a may fit under the arm pits of the wearer. This may be done by the wearer lifting his arms up over the inflated portions 11 and 11a. The entire inflated chambers cannot move back to any objectionable extent as they are held substantially as shown by the chest straps and interconnected snaphooks 64, 64a.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. A life preserver adapted to be worn at about 70 waist height including belt means having a pas-

sageway therein, means depending from said belt means having an opening in communication with said passageway, said depending means comprising an outer wall forming a pocket and an inner wall normally disposed within said outer wall and forming a pocket therein, and strap means having a portion connected with and extending along said pocket when deflated and having another portion extending along said pocket and connected with said first strap portion and spaceable from said pocket and the first strap portion to facilitate insertion of an arm between said strap portions.

2. A life preserver adapted to be worn at about waist height when deflated including belt means having a passageway therein, means depending from said belt means having an opening in communication with said passageway, said latter means comprising an outer baglike element and an inner baglike element normally disposed within said outer baglike element, means carried by said inner element to facilitate attachment to an article of clothing, and strap means having a portion connected with at least one of said elements and extending along said outer element when deflated and having another portion extending along said outer element and connected with said first strap portion and spaceable from said outer element and the first strap portion to facilitate insertion of an arm between said strap portions.

3. A life preserver adapted to be worn at about waist height including belt means having a passageway therein, a plurality of means depending from said belt means at spaced intervals each having an opening in communication with said passageway, each of said depending means comprising an outer wall forming a pocket and an inner wall normally disposed within said outer wall and forming a pocket therein, and strap means connected to said belt means and to said depending means at locations spaced below said belt means and including portions extending along said outer pockets when deflated and being spaceable from said outer pockets to facilitate insertion of arms between said outer pockets and strap portions.

4. A life preserver as claimed in claim 3, in which said belt means has connected therewith means for attaching it to a pair of trousers.

5. A life preserver as claimed in claim 3, in which said strap means includes a portion extending along the belt means and joining together the strap portions which extend along said outer pockets.

10 6. A life preserver as claimed in claim 3, in which additional strap means is connected to at least one of said outer pockets and means is connected to another of said pockets whereby said additional strap means may be connected thereto for joining the pockets with each other at a location spaced from the belt means.

15 7. A life preserver adapted to be worn at about waist height including belt means, a plurality of means depending from said belt means at spaced intervals each bearing an opening for admitting gas thereto, each of said depending means comprising an outer wall forming a pocket and an inner wall normally disposed within said outer wall and forming a pocket therein, and strap means having portions connected with and extending along said depending means when deflated and having other portions extending along said depending means and connected with said first strap portions and spaceable from said depending means and said first strap portions to facilitate insertion of arms between said strap portions.
